UNITED STATES PATENT OFFICE.

FRANK E. LYON, OF DUBUQUE, IOWA.

MACHINE FOR COVERING PIANO-STRINGS.

SPECIFICATION forming part of Letters Patent No. 515,597, dated February 27, 1894.

Application filed March 15, 1893. Serial No. 466,076. (No model.)

To all whom it may concern:

Be it known that I, FRANK E. LYON, a citizen of the United States, residing at Dubuque, in the county of Dubuque and State of Iowa, have invented certain new and useful Improvements in Machines for Covering Piano-Strings; and I do hereby declare the following to be a full, clear, and exact description of the invention, such as will enable others skilled in the art to which it appertains to make and use the same.

My invention relates to a machine for producing piano strings and the like which are formed by spirally winding wire upon a central core of wire, and it consists of certain novel constructions, combinations and arrangements of parts as will be hereinafter described and claimed.

In the accompanying drawings, Figure 1 is a side elevation partly in section of my improved machine. Fig. 2 is a longitudinal section, partly in elevation of the same, and Fig. 3 is an end view of the guide and tension feed plate.

25 A in the drawings represents my improved machine for making piano strings and the like, and it consists of a stationary base B provided with a longitudinal groove *b* in which is journaled a suitable number of rollers *b'*. 30 Within this groove and upon the rollers a longitudinally movable carriage C is placed and is adapted to move backward and forward with as little friction as possible.

D, D are brackets secured to the top surface of the carriage by pins *d* extending down from the brackets and resting in holes *c* in the top of the carriage, and held by screws *c'*. A series of these adjusting holes *c* may be provided along the top of the carriage for bringing the brackets D, D closer together or farther apart accordingly as it is desired to cover a short or long string. On these brackets the core wire E to be wrapped is tightly stretched and held so as not to revolve, one end being hooked on one of the brackets and the other end held by a tension device of any suitable construction on the other bracket.

45 F, F are stationary supports secured to the base and sustain the hollow shaft or arbor G, which is hollow from end to end. Secured to this shaft or formed with it is a pulley J over

which a belt is passed to operate the machine. On the left hand end of the hollow shaft or arbor a reel or drum I carrying the wrapping wire M is loosely journaled, which when all the wire is wound from off of the same can be slipped off that end of the shaft by unscrewing the guide and tension plate H from the shaft, and be replaced by a filled reel. 55 60

Between the reel and one of the supports F a collar K is shrunk or permanently fixed on the shaft or arbor G as shown, to prevent the reel having a lateral movement in that direction, it being prevented from moving in 65 the opposite direction by the guide and tension plate H. As stated above, the tension and guide plate H is screwed onto the end of the shaft or arbor G and consists of a revoluble, centrally perforated circular metal 70 disk formed with a hub extension *h* on its outer surface and having its central opening filled or closed by a centrally perforated core *h'* of wood or other non scratching solid substance. 75

On the outer face of the tension and guide plate between the hub extension and its outer periphery it is provided with a tension device *h*² between which and the outer face of the plate H the wrapping wire M is passed 80 and held at any desired tension by the thumb screw *h*³ as shown. The passage through the plug or core of wood *h'* in the plate H is just about the same size as the core wire passed through it, and this is found of great importance, as the wrapping or covering wire which passes from off the reel through an opening *h*⁴ in the plate H near its outer periphery, thence under the tension device and down through the outwardly extended hub *h* onto 90 and around the wire F, will be crowded in between the first wrap or wind which has been made around the stretched core wire F and the perforated plug or core *h*, and automatically force the carriage carrying the 95 stretched core wire F forward, as fast as the wire F is wrapped, this result being due to the fact that the perforation in the plug or core *h* is not large enough to permit the wrapped wire to press into the same, and to 100 the fact that the only part of the machine which is movable longitudinally being the carriage and the wire carried thereby which must necessarily give way and be forced forward.

When a wire F is completely wrapped or covered the desired length it is removed from the machine by unfastening it from the brackets D, D. Piano strings are highly polished and any rubbing or friction on the same while being wrapped would practically destroy the string, consequently it is very important that as far as possible the wire be not brought in contact with any wearing surface, and that where such contact is necessary, a wearing surface of wood or other similar substance should be employed to protect the wire from injury. It is to accomplish this object that I construct the central core h' of the plate H of wood, and also construct the carriage to move with as little friction as possible and stretch the wire F as tightly as possible.

What I claim as my invention is—

1. In a machine for covering piano strings and the like, the combination of a suitable base having vertical supports, a hollow shaft journaled in said supports, a drum, reel and guide and tension plate all centrally arranged on said shaft in the same axial line and having a rotary movement only, a longitudinally movable carriage provided with means for carrying and holding a non revoluble core wire by both of its ends, at a proper tension while being wrapped, the said core wire when secured to the carriage passing through the hollow shaft, drum, reel and tension plate, the passage through the tension plate being smaller in diameter than the core wire when wrapped, so that the covering wire as it is being wrapped around the core wire will move the carriage forward automatically without any other feeding means, substantially as described.

2. In a machine for covering piano strings and the like the combination of a suitable guiding base having vertical supports, a longitudinally arranged hollow shaft journaled in said supports, a drum, reel and guide and tension plate all arranged on said shaft in the same axial line and having a rotary movement only; the tension plate having a clamping disk and a radially perforated hub like extension, the tension disk being applied to one of the faces of the tension plate and provided with a regulating tension screw so that the covering wire will be caused to pass toward the core wire in a direction practically at a right angle; a longitudinally moving carriage provided with means for carrying and holding a non revolving core wire by both of its ends at a tension while being wrapped, the said core wire when secured to the carriage passing through the hollow shaft, drum, reel and tension plate, the passage through the

tension plate being smaller than the diameter of the core wire when wrapped, so that the covering wire as it is being wrapped around the core wire will move the carriage forward automatically without other feeding means, substantially as described.

3. In a machine for covering wire the combination of a suitable base, vertical supports, a revolvable longitudinal shaft journaled in said supports and having a central opening through it, a centrally perforated reel and a centrally perforated guide and tension plate arranged on said shaft in the same axial line, a longitudinally movable carriage carrying a non revolvable core wire which passes centrally through the shaft, reel and tension plate, adjustable wire attaching brackets on the carriage and two or more adjusting holes in the same for moving the said brackets nearer to or farther from each other, substantially as described.

4. In a wire wrapping machine, the combination of a grooved guiding and supporting base having a roller bed, supports secured to said base, a hollow shaft journaled in said supports and carrying a drum, reel and guide and tension plate all having a rotary movement only, a longitudinally moving carriage provided with means for carrying a non revolving core wire by both of its ends at a tension while being wrapped, the said core wire when secured to the carriage passing through the tension plate, the passage through the tension plate being smaller in diameter than the core wire when wrapped, whereby the covering wire as it is being wrapped around the core wire will move the carriage and the core wire carried thereby, forward automatically without other feeding means, substantially, as described.

5. In a wire covering machine, the combination of a reel for holding and feeding a covering wire, means for imparting a rotary movement only to said reel, and a longitudinally movable carriage provided with means for holding and carrying at a tension a non revolvable core wire to be wrapped, the said carriage and core wire being moved forward automatically and without other feeding means by the covering wire as it is being wrapped around the core wire, substantially as described.

In testimony whereof I hereunto affix my signature in presence of two witnesses.

FRANK E. LYON.
